FABRIC EDGING

Rudolf Loeb, Jenkintown, Pa.

Application April 21, 1934, Serial No. 721,787

7 Claims. (Cl. 112—266)

This invention relates to the construction, and to the method of making, a new and novel type of edging for textile fabrics; and particularly to an edging for those more or less flimsy or delicate fabrics of the open-weave, mesh or net types such as are commonly employed in the making of the bodies and/or trimmings of various kinds of furniture covers or scarfs and draperies including curtains, valances, tie-backs, etc.

In the case of draperies, the trimming frequently takes the form of a single row or series of rows of ruffles at or adjacent one or more edges of the article. A specific application of the present invention resides in an edging for a strip of fabric from which a trimming ruffle of the aforementioned kind is made.

The construction of the edging forming the subject of the present invention and the method by which such edging is produced will be fully disclosed hereinafter, reference being had to the accompanying drawing; of which:

Fig. 1 is a fragmentary face view of a piece of material illustrating the edging of the present invention as applied thereto;

Fig. 2 is a face view of the edging per se;

Fig. 3 is a face view of the fabric prior to the application of the edging thereto; and

Fig. 4 is a cross section taken on the line 4—4, Fig. 1.

As shown in the drawing, 1 indicates a piece of fabric of the net, mesh, or open-weave type, such as one will commonly find in draperies for the windows of private homes. Usually such curtains are hung in pairs with a valance at the top of the window and with strips, known as "tie-backs", holding the curtains draped in a semi-festoon at each side of the window. The curtains are frequently trimmed along their inner vertically hanging edges and along their lower horizontal edges with a single row of ruffles also constructed of the fabric of the type illustrated at 1 and the valance and tie-backs are usually made of the same fabric and adorned in a like manner.

In order to produce these ruffles, the wider pieces of material, such as those of which the bodies of the curtains are formed, are cut into relatively narrow strips of a width corresponding to the depth of the ruffle desired. The one cut edge of the ruffle strip is folded in and hidden as the ruffle is being stitched to the body of the article. The opposite, or free, cut edge of the ruffle strip is frequently hemmed in a conventional manner to hide such cut edge. In other instances, as illustrated in Fig. 3, this free edge is either rolled or puckered laterally, as illustrated at 2, and held

in this form by means of a series of zig-zag or over-edge stitches, illustrated at 3, which penetrate and are locked in the fabric at points 4, 4, located inwardly of the rolled edge 2, and again locked together, outside the roll 2, at points illustrated at 5, 5.

The edging constituting the subject matter of the present invention is adapted to be applied to the free edge of the ruffle, in addition to the hem or roll or puckering 2, as the case may be, for the purpose of ornamenting the free edge of the ruffle.

As shown in Fig. 2, this edging consists of a row of chain stitches 10 which runs in a substantially straight line. At predetermined intervals throughout the length of the chain 10, the stitches 15 are diverted laterally from the straight line of the chain 10 to form suitable appendages, such as rings or loops 11, 11, thereon.

Each of the appendages 11 consists of a predetermined number of the stitches 12 which are interlocked with each other in, and collectively 20 form, an ornate figure around an open center 13.

The stitches 12, upon completing the open centered figure, overlap the stitches of the chain 10 at the point at which the stitches of the chain 10 were diverted from the straight line of the 25 chain to form the appendage, whereupon the formation of subsequent successively interlocked stitches is continued in the straight line of the chain 10, to the point where another of the appendages 11 is to be produced.

This operation is followed out along the length of the edging, at predetermined intervals corresponding to the spacing of the appendages 11 which preferably, though not necessarily, are uniformly spaced along the length of the edging.

The production of the edging shown in Fig. 2, preferably is effected simultaneous with the application of the edging to the fabric, for example, a piece of fabric 1, such as that illustrated in Fig. 3, is run through a suitable sewing or embroidery machine capable of producing the chain of stitches 10. The fabric is fed to the machine in such a manner that the needle or hook for producing the chain stitches 10 penetrates the fabric 1 on or immediately adjacent the inner or back edge of the roll or hem 2, at or near and substantially parallel to the line of the penetrating points 4 of the zig-zag or overedge stitches 3.

The machine is operated normally until a predetermined number of the stitches constituting the chain 10 have been formed in a straight line, adjacent the edge 2 of the fabric, whereupon either the fabric, or the needle, or the hook forming the stitches of the chain 10 is actuated

in a manner to divert the formation of the stitches from the straight line of the chain 10 as successive stitches are subsequently formed, whereby the formation of the interlocked stitches passes off and beyond the edge 2 of the fabric 1 and are locked one with the other beyond said edge to produce the shape and size of the appendage 11 which is desired.

The continued turning of the fabric relative to 10 the needle or the turning of the needle relative to the fabric, as the case may be in forming a ring 11, is carried on until the stitches forming the ring again cross the edge 2 of the fabric and overlap the stitches of the chain 10 at the last 15 point of diversion, whereupon another series of stitches in a straight line, and in line with the previously formed stitches of the chain 10, is made, up to the point where another appendage 11 is desired. This cycle of operations is 20 repeated continuously along the edge of the fabric.

In the preferred form of the invention there are four straight successively formed and interlocked stitches in each straight section of the edging between each two of the appendages 11, 11 25 and each of the rings 11 is composed of four successively formed and interlocked stitches arranged around the open center 13 of the appendage.

The esthetic effect of the edging may be enhanced by using a thread, in the formation of the 30 edge 2, of a different color from the body of the fabric, for example, the over-edge stitches 3 may be black while the fabric 1 is white and by making the stitches which constitute the superimposed edging of the present invention, including 35 the chain 10 and appendages 11, of a thread differing in color from both the fabric 1 and the over-edge stitches 3, for example, a pale blue or green.

The zig-zag or over-edge stitches 3 are common 40 in the art and may be readily produced by a well known Willcox and Gibbs over-edge sewing machine. The edging consisting of the chain 10 and lateral appendages 11 may be formed by any suitable type of machine adaptable for the purpose and in the present instance is produced by a well known type of embroidery machine modified and provided with suitable attachments adapted to cause the needle to depart from the straight line stitch formation to produce the ornate appendages along the edge of the fabric periodically.

I claim:

1. An article of manufacture comprising a piece of relatively open textile material having a bound 55 margin provided with an additional edging comprising a continuous chain of successively formed and interlocked stitches disposed in a substantially straight continuous line spaced inwardly from the bound margin of said piece with ornate 60 appendages composed of stitches of said chain extending laterally from said line and outwardly beyond said bound margin at predetermined points throughout the length thereof.

2. An article of manufacture comprising a 65 piece of relatively open textile material having a bound margin provided with an additional edging comprising a continuous chain of successively formed and interlocked stitches disposed in a substantially straight continuous line substantially parallel to said bound margin with ornate 70 appendages composed of stitches of said chain extending laterally from said line and overlying and projecting outwardly beyond said margin at predetermined points throughout the length 75 thereof.

3. An article of manufacture comprising a piece of relatively open textile material having a marginal edge bound by overedge stitching, said article being provided with an additional superimposed edging comprising a continuous chain of successively formed and interlocked stitches disposed in a substantially straight continuous line substantially parallel to said bound margin with ornate appendages composed of stitches of said chain extending laterally from said line and overlying and projecting outwardly beyond the overedge stitching binding said margin, said appendages being disposed at predetermined points throughout the length thereof. 5

4. An article of manufacture comprising a piece of relatively open textile material having a marginal edge bound by overedge stitching, said article being provided with an additional superimposed edging comprising a continuous chain of successively formed and interlocked stitches 10 disposed in a substantially straight continuous line substantially parallel to said bound margin with ornate appendages composed of stitches of said chain extending laterally from said line and overlying and projecting outwardly beyond the overedge stitching binding said margin, said appendages being disposed at predetermined uniformly spaced points throughout the length thereof. 15

5. An article of manufacture comprising a piece of relatively open textile material having a marginal edge bound by overedge stitching, said article being provided with an additional superimposed edging comprising a continuous chain of successively formed and interlocked stitches 20 disposed in a substantially straight continuous line substantially parallel to said bound margin with ornate appendages composed of stitches of said chain extending laterally from said line and overlying and projecting outwardly beyond the overedge stitching binding said margin, said appendages being disposed at predetermined uniformly spaced points throughout the length thereof. 25

6. The method of producing an ornate edge on 30

a piece of textile material which consists in forming a row of overedge stitches along one edge of the piece, by anchoring said overedge stitches in the material inwardly from said edge and extending said stitches around said edge to bind said edge, then forming a continuous line of successively interlocked chain stitches on and adjacent said edge of the piece, at predetermined intervals along said edge diverting the formation of said chain stitches laterally outward from the continuous line of the chain to and beyond said edge of the piece in superposed relation to said overedge stitches, returning with the formation of said chain stitches across said edge to the point of diversion from said continuous line of the chain, and continuing the formation of said continuous line of chain stitches from said point of diversion in alignment with that portion of said line produced prior to said diversion therefrom. 45

7. The method of producing an ornate edge on a piece of textile material which consists in forming a row of overedge stitches along one edge of the piece, by anchoring said overedge stitches in the material inwardly from said edge and extending said stitches around said edge to bind said edge, then forming a continuous line of successively interlocked chain stitches on and adjacent said edge of the piece in a position substantially coincident with the line of anchorage of 50

said overedge stitches, at predetermined intervals along said edge diverting the formation of said chain stitches laterally outward from the continuous line of the chain to and beyond said edge 5 of the piece in superposed relation to said over-edge stitches, returning with the formation of said chain stitches across said edge to the point of

diversion from said continuous line of the chain, and continuing the formation of said continuous line of chain stitches from said point of diversion in alignment with that portion of said line produced prior to said diversion therefrom. 5

RUDOLF LOEB.
